UNITED STATES PATENT OFFICE.

EDWARD M. LOCKWOOD, OF PHILADELPHIA, PENNSYLVANIA.

EMBOSSING AND PRINTING PRESS.

1,102,770.

Specification of Letters Patent.

Patented July 7, 1914.

Application filed February 5, 1914. Serial No. 816,661.

To all whom it may concern:

Be it known that I, EDWARD M. LOCKWOOD, a citizen of the United States, and resident of Philadelphia, county of Philadelphia, and State of Pennsylvania, have invented an Improvement in Embossing and Printing Presses, of which the following is a specification.

This invention relates to embossing and printing presses, and consists of certain improvements which are fully set forth in the following specification and shown in the accompanying drawings which form a part thereof.

One of the objects of my invention is to provide a mechanism for use as a unitary part of a complete machine for printing and embossing whereby the wearing surface of thrust or like bearings may be varied or shifted from one point of application to another, and thus not only save wear on said bearings but also distribute the lubrication for the bearing or bearings, so that the wearing surface is always maintained properly lubricated.

In connection with the foregoing object the invention has for a further object to automatically control the movement of the aforesaid thrust or pressure applying members.

In practice in machines of this character, it has been found that the heavy pressure required for efficient operation causes the lubricating fluid or material to be squeezed or pressed out between the contacting or wearing surfaces of the bearings, with the consequent result of undue wear upon the parts.

It is therefore one object of my invention to overcome the foregoing defects.

The invention has for a further object, to provide alinement of divided guides for the die carriage, so that the carriage may freely reciprocate in said guides and from one part thereof to the other irrespective of the vertical position of the carriage and one part of guides in which it may be held with respect to the other part, whereby the carriage is always in proper association with the entire guide portions for horizontal reciprocation irrespective of any vertical adjustments to the carriage.

My invention has for a further object to provide automatic feeding mechanism for

the ink wiping web used to wipe the die carried by the carriage, which may be adjusted and regulated at the will of the operator to vary the length of the wiping web supplied with each reciprocation of the carriage.

It has for a further object, to provide a manually operable feeding means for the wiping web, said means operating as an auxiliary adjunct of the automatic feeding mechanism, whereby the wiping web may be fed at times when the machine is at rest.

My invention consists of devices and means for efficiently accomplishing the aforesaid objects of my invention as more fully set out hereinafter and defined in the claims.

Referring to the drawings:—Figure 1 represents a vertical section of a press embodying my invention; Fig. 2 represents a side elevation of a portion of the press showing the journal actuating mechanism for the press plunger; Fig. 3 represents an end elevation of the same; Fig. 4 represents an end elevation of the upper press plunger and its adjuncts; Fig. 5 represents a side elevation of the same; Fig. 6 represents a detail of the driving device for the main rock shaft; Fig. 7 represents a section of the wiping web feeding mechanism used in connection with the wiper block; Fig. 8 represents a side elevation of a portion of the control mechanism for the wiping web feeding mechanism; Fig. 9 represents an end elevation of the parts shown in Fig. 7; and Fig. 10 represents a detail of the feed mechanism.

Similar numerals of reference indicate corresponding parts.

1 designates the main frame of the machine, which consists preferably of two side frames connected by suitable cross frames and may be of any desired construction.

2 designates a set of guides arranged substantially horizontal and serving to horizontally guide the reciprocable carriage 3 which is provided with the adjustable die-clamps 4. The carriage 3 is connected with a rock lever 5 by means of links 6 and 7 which are pivoted together upon a transverse shaft 8 and form a mechanism permitting a dwell in the reciprocation of the carriage. The ends of the shaft 8 are provided with suitable guide rollers 8^a for cooperation with the guide ways 9 and 10 which are suitably spaced apart, and have

one portion thereof arranged substantially horizontal while the remaining portion is curved and concentric with the axis of the link 6 on the carriage 3. By this construction it will be apparent when the carriage 5 is in the position shown in Fig. 1 that the rearward movement of the arm or lever 5 will cause the link 6 to swing backward and upward without disturbing the carriage, 10 thereby giving to it a period of dwell to perform the printing and embossing, and subsequently when the shaft 8 passes above the curved portion of the guideway the links 6 and 7 will have straightened into approximate alinement and at which time a further 15 movement of the arm 5 will impart movement to the carriage 3 along the guides 2. In connection with this construction, attention is directed to the fact that the two 20 guides 9 and 10 are connected together as shown at 11 and are also fixed to the guides 2, and the two sets of guides in turn are pivoted at 12 to the main frame in order to swing together at certain times, as will be 25 later described.

The machine is driven from any suitable source of power, such as the motor 13, and transmits motion by way of the belt 14 to the pulley 15 which is mounted upon the 30 main shaft 16, the latter being suitably journaled in the main frame of the machine. Power is transmitted from the shaft 16 through suitable gears 17 to a cam shaft 18, which latter also carries a wheel 19 35 having a wrist-pin 20 secured thereto by means of which an oscillating movement is transmitted to the rock shaft 21 and its arm 5 through the medium of the arm 22 and crank link 23, this latter being detachably 40 connected to the wrist-pin 20. The rock shaft 21 has fixed thereto the lever 5 and thus causes actuation of the parts controlling the reciprocating action of the carriage 3.

45 24^a designates a guide for a vertical die carrying plunger 24 arranged at the front and upper portion of the machine. The plunger 24 is adjustably connected to a pin 26 of a toggle link 27 by a mechanism comprising guide blocks 28 mounted in guideways at the upper portion of the plunger, said guide blocks in addition serve as journals for the pin 26 and having transverse guides to receive the laterally disposed 50 flanges 28^a of a wedge member 29. This member 29 is also provided with flanges 30 at the bottom which slide in grooves or guides 31 of a portion of the plunger 24. The wedge member 29 is movable through 55 the medium of a feed screw 32, the operation of which is controlled by the hand wheel 33. A set nut 34 is also provided to hold the wedge member 29 immovable when adjusted through the medium of a feed 60 screw 32.

35 designates the second member of the toggle mechanism and the same is hinged at 36 to the head 37. It will further be noted that both the member 35 and link 27 are each provided with a lug 38, one being 70 adapted to abut the other and serve as a stop to limit the movement of the link 27 in one direction. This toggle mechanism is straightened and operated by a pin 39 carrying the link 40, which connects with an arm 41 receiving a rocking movement through the shaft 42, lever 43 and rod 44, the latter being actuated by a pivoted arm 45, and the cam roller 46 operating in a groove of the cam 47. This cam 47 is 75 mounted upon the shaft 18. The aforesaid mechanism serves the purpose of imparting a comparatively small movement to the die-head 25, but yet is sufficient to permit free movement of the carriage 3 beneath it, and 80 the easy introduction and removal of the paper. The movement of the die head 25 is, however, relatively large with respect to the vertical movement of the carriage 3 and the die clamp 4 carried thereby. 85

In my present invention, the plunger 24 and die member 25 really serve as an abutment against which the pressing mechanism exerts its pressure, this latter mechanism being located at the lower portion of the 90 machine.

48 designates a movable table carried by the plunger 49 and having a suitable set of guides 2^a thereon to receive the carriage 3, which guides are also alined with the guides 100 2 and are normally interlocked therewith, so that as the table 48 moves up or down the free ends of the guides 2 likewise receive the same motion and hence both sets or portions of carriage guides will always be in 105 alinement, and these guides 2^a positively hold the carriage laterally in position upon the table and plunger. The plunger 49 is suitably guided in a head 50 fixed to the 110 frame 1 and is operated by means of the toggle members 51 and 52.

53 designates a bearing pin interposed between the plunger 49 and the member 51, the said pin being journaled or seated in suitable thrust blocks 54. 55 and 56 designate respectively similar bearing pins between the toggle members 51 and 52 and between the member 52 and the base plate 57. These latter pins are journaled in similar blocks to those for the pin 53 and hence 115 I have preferred to designate these blocks with the same reference numerals. I have used the term pin for the parts 53, 55 and 56 merely as a convenient one, and it will be understood from the function of these 120 parts that they might equally well be termed shafts, pintles, bearing members or the like.

The toggle made up of the foregoing mechanism is operated by a cam roller 58 journaled in a bracket 59 fixed to the block 130

52, and the said roller 58 carries on its journal a yoke 60 which is apertured to receive the shaft 18. Upon the opposite side of the shaft 18 from the roller 58 there is a second roller 61 riding upon the periphery of the cam 62, which is mounted for rotation with the shaft 18 and provided with a depression 63 opposite to which is the cam lug 64. It will therefore be apparent, as the 5 said cam rotates, that the lug 64 will operate to shift the roller 58 to straighten the toggle while continued movement of the cam will cause the roller 61 to shift the yoke and thus break the toggle. At the time the toggle 10 is straightened the plunger 49 will be forced upwardly to bring the carriage and dies to operative position and the necessary heavy pressure for the work be properly transmitted. This pressure causes the pins 15 to tend to wear rapidly and even when properly lubricated the oil or other lubricant is squeezed out during the pressing operation and thus subjects the pin to substantially as much wear as if there were no lubrication. 20 In order to obviate this disadvantage I have in the present instance provided a ratchet wheel 65 for each of the pins 53, 55 and 56, the said ratchets being keyed or otherwise secured to the respective pins and intermittently actuated by pawls 66 carried by one 25 arm of a bell crank lever 67 loosely mounted upon the respective pins. The several bell cranks are connected together by links 68 and 69 so that the operation of one bell 30 crank will cause a similar movement to be transmitted to the remaining bell cranks. As here shown, motion is imparted to one of the bell cranks by a connecting rod 70 pivoted at one end to a rock lever 71, which 35 also serves to control the movement of the inking roll at the proper time. It will be understood that the rod 70 may be connected to other suitable moving parts of the mechanism, or independently actuated as 40 desired.

Having referred to the inking roll, I will now describe the operation of the same and its relation to the movable carriages.

The lever 71 is connected at its upper end 45 to a rock spindle 72 which carries the inking roll 73 and is adapted to move the latter from contact relation with the supplying roll 74 to a position substantially in the path of the carriage 3, so that the die clamp 4 upon the latter may pass into contact therewith and have the ink distributed upon the surface of the die. The ink supplying roll 55 74 is rotatably mounted in a suitable ink reservoir 75. The arm 71 is pivoted at 60 76 intermediate its ends and has its lower end connected by a link 77 to a rocker arm 78, this latter being pivoted upon a suitable spindle 79 and carrying a roller 80. This roller 80 rides in a cam groove of the cam 65 81 which is carried by the cam shaft 18, and

the parts are of course so designed and arranged as to impart the desired rocking movement to the arm 71 at the proper time in the cycle of operation. It will be noted in connection with this action that the cam 70 81 is so timed that the ink applying roll 73 is advanced and held stationary at the time the carriage 3 is being reciprocated beneath it.

82 designates the wiper plate, preferably 75 provided with a suitable cloth pad 83 across the face of which the wiping material such as a paper web or the like is adapted to be fed and is here indicated in dotted lines at 84. The mechanism for causing the usual vertical reciprocation of the wiper member has been omitted as any suitable means may be employed for this purpose, but it will be understood that the wiper 82 is to be raised when the carriage 3 moves rearward of the 80 press in order not to be in contact with the die during its travel to position to receive the ink. When, however, the carriage makes its return movement, that is, is moved forward toward its printing position, the 85 wiper 82 is lowered for the purpose of wiping the surplus ink from the surface of the die before the embossing and printing take place.

The means for feeding, guiding and controlling the actuation of the wiping web will 90 now be described.

85 designates a supporting shaft journaled at a convenient point on the frame 1, and having a roll of paper which is adapted 100 to be guided beneath the feed roller 86, then over the rod 87 passing thence beneath the wiper pad 83 and thence upward to the winding shaft or mandrel 88. The mandrel 88 is removably mounted between suitable 105 spindles 89, one of which is shown in Fig. 7 and rotates therewith through the medium of ears or lugs 90 which are adapted to seat in suitable apertures or slots in the end of the mandrel. In view of the fact that the 110 die on the carriage 3 is only required to coact with the wiper 82 at certain intervals, it is of course unnecessary to provide a continuous feed for the paper 84, and accordingly I have provided an intermittent action to rotate the mandrel 88 as occasion demands, and permit only enough paper web 115 to be fed across the face of the wiper at each operation to present a clean surface necessary to insure the wiping of the die to 120 the requisite degree. This intermittent mechanism comprises a frame 91 fixed to the main frame of the machine and having journaled therein a sleeve 92 carrying the pinion 93, which latter is in mesh with a gear 94 125 upon the shaft 95. The sleeve 92 forms a bearing for the spindle 89, and transmits its motion thereto through the medium of a leather or other friction disk 96 which is interposed between the plate 96 on the end 130

of the pinion 93 and a ratchet wheel 97 fixed to the said spindle 89. The friction between the aforesaid parts is controlled and regulated by a spring 98 bearing at one end 5 against a part connected to the frame 91 and at its opposite end against an adjusting collar 99 threaded to the spindle 89. The tension of this spring 98 may be adjusted by adjusting the collar 99 on the spindle 10 and locking it in position thereon by the split sleeve 99a screwed thereon and clamped in position.

100 designates a hand wheel or the like for manually rotating the mandrel 88 to 15 wind the wiping material under certain conditions.

The ratchet 97 is held against movement in one direction by means of the usual spring controlled pawls 101 which are suitably 20 mounted on the frame 91. Motion is transmitted to the spindle 95 by means of a pinion 102 normally meshing with a rack 103 which is mounted for reciprocating movement within the guide head 104 and is 25 operated by the connecting rod 105 pivoted at its lower end to a block 107, said block adjustably mounted in a guide frame 108 suitably pivoted to the main frame 1. In 30 order to fix the radial position of the block 107 with respect to the pivotal point of the frame 108, I have shown the same threaded upon the spindle 109, which latter terminates in the operating handle 110. This construction affords a means for varying the 35 stroke of the connecting rod 105 and thus determines the movement of the rack 103. The frame 108 is oscillated by the link 111 jointed at 112 to a rocker arm 113 fixed to the rock shaft 21. It will thus be apparent 40 that the rack 103 on its downward stroke, will cause the pinion 102 to transmit movement to the gear 94, thereby rotating the pinion 93 and through the friction clutch 45 cause the mandrel 88 for the paper web to rotate in the direction of the arrow shown in Fig. 1, namely, to wind a certain length of the paper web upon the mandrel. Another adjunct of the feeding mechanism is the 50 guide roll 86, between which and the pressure roll 114 the paper passes on its way to the wiper device 82. The feeding roll 86 is operated substantially simultaneously with the movement of the mandrel 88, by means of a pawl and ratchet movement 55 controlled by the chain 116 which passes over a sprocket wheel 117 and has its outer end connected to the rack 103. The chain 116 also is secured to and passes about the sprocket wheel 118 on the shaft 119 of the 60 feed roller 86, the said sprocket being fixed to a collar 120, carrying the pawl 121 of the ratchet movement, so that movement of the said collar in the proper direction causes the ratchet wheel 115 to turn the feed roller

to the degree desired. The proper tension 65 on the chain 116 is maintained by a suitable cord 112 which is fixed to and passes over the collar 120, and also over an idle pulley 123 beyond which it terminates in a counter-weight 124. Should it be desired to actuate the feed roller 86 when the automatic feeding mechanism is not in operation, I have provided a hand lever 125 pivoted at 70 126 to the guide plate 104 and carrying also the sprocket wheel 117. By oscillating this 75 lever, the feed roller 86 draws out a length of paper web which may be taken up by manually turning the member 100 of the mandrel.

127 designates an extension of the lever 80 125 projecting into the path of movement of the pivot 116 and serving the purpose of preventing the hand lever 125 from moving out of position during the automatic feeding operation.

In the operation of the machine it will be assumed that the parts are in the position shown in Fig. 1 and a printing or embossing step has just been completed. The continued operation of the machine causes the 90 cam 62 to rotate and shift the roller 61 so that, through the yoke 60, the lever arm 59 is swung in a direction to break the toggle formed by the members 51 and 52 and thus lower the press plunger 49 and table 48. 95 At the time this action takes place the rod 70 is actuated by the cam 81 to shift the bell crank 67 and cause the ratchet wheel 65 to give a partial rotation to the pin 53. The same movement is likewise given to the pins 100 55 and 56 through the medium of the connecting levers 68 and 69, and consequently all of the pins are partially turned so that a freshly lubricated portion of each pin comes into place to take the pressure of the 105 next printing operation and thus save wear upon the pins. At the same time that the rod 70 performs its function, the arm 71 is actuated to swing the ink roller 73 from its position in contact with the ink supplying 110 roll 74 to a position in the path of the die 4 carried by the carriage 3. During this short interval of time the lever 5 has been rocked rearwardly by the movement of the shaft 21, thus straightening the toggle of the links 6 115 and 7 so that the carriage 3 with its die is moved to the rear of the machine along the guides 2, the die passing beneath but out of contact with the wiper member 82 and into engagement with the roller 73, where it is 120 inked for a new printing operation. The movement of the rock shaft 21, to shift the lever arm 5, also causes the rack 103 to move downwardly and thus rotate the mandrel 88 to wind a predetermined quantity of the 125 wiping paper web from the roll 85 and bring a clean surface of paper into position upon the wiper 82. The movement of the

rack 103 unwinds also a portion of the chain 16 so that the feed roller 86 operates synchronously with the winding movement of the mandrel 88. After the inking operation, the rock shaft 21 reverses its movement and returns the carriage and its die toward the forward portion of the machine, and as they pass the wiper pad 83 the mechanism controlling the movement of the said wiper comes into operation and lowers it into contact with the inked surface of the die so that all superfluous ink is removed before the carriage actually returns to its normal printing or embossing position (Fig. 1). It will further be noted that the cam 47 is properly timed to actuate the rod 44 controlling the toggle formed by the members 27 and 35, and consequently the upper plunger 24 is adapted to be moved away from the carriage 3 at substantially the same time that the lower plunger 49 is dropped. On the return of the carriage to normal position the rod 44 brings the toggle member 27 back to its normal position, so that the plunger 24 becomes a fixed abutment to receive the heavy pressure transmitted by the small movement of the lower plunger 49. Should it be desired to vary the quantity of paper web fed to the mandrel 88, the hand lever 110 may be turned so as to vary the throw of the oscillating frame 108 and thus change the stroke of the rod 105. In case it is desired to feed the paper web when the machine is not in operation, the lever 125 is manually operated and the desired quantity of paper web unreeled. It will be noted further that the upward movement of the table 48 is accomplished without affecting the relation between the guides on the table and the guide members 2, thus permitting the carriage 3 to travel uninterruptedly from one part to another. Thus as the table 48 rises to impart pressure, it carries with it the free ends of the guides 3 which swing about the pivot 12 and maintains the proper alignment.

Attention is particularly directed to the toggle mechanism and its adjuncts for controlling the movement of the plunger 49 and the carriage, in view of the fact that the movement imparted to the bearing pins of the toggle is an important component of my invention. While the reciprocating movement of the plunger 49 is very limited, the pressure transmitted to this plunger is very heavy and consequently the parts embodied in the power transmitting means must be designed to stand the wear and strain of the printing or embossing action. As these pins are seated in suitable wear or bearing blocks, and are also provided with lubrication it is evident that unless the wearing surfaces of the pin and the blocks are varied with respect to each other, the tendency of

the pressure will be to squeeze or work the lubricant away from the wearing surface. This condition I have overcome by providing a means for intermittently changing the relation between the respective pins and the wear blocks so that after one surface has been exposed to the pressure, another surface carrying a coating of lubrication will move in a position to receive the thrust during the following operation.

It will now be apparent that I have devised a novel and useful construction which embodies the features of advantage enumerated as desirable in the statement of the invention and the above description, and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim and desire to protect by Letters Patent of the United States is:—

1. In an embossing and printing press, the combination of a reciprocable die actuating plunger, an abutment for receiving the thrust of the plunger, power devices for reciprocating said plunger, means having oscillating parts for transmitting thrust from said devices to said plunger, and means for automatically renewing the surfaces subjected to thrust pressure between said transmitting means and said plunger, whereby different wearing surfaces of said transmitting means are, during periods intermediate of the printing periods, successively brought into position to receive the thrust.

2. In an embossing and printing press, the combination of a reciprocable plunger, an abutment for receiving the thrust of said plunger, power devices for reciprocating said plunger, a pin rotatably mounted and forming a power transmitting means between said power devices and said plunger, and means for automatically causing an intermittent positive rotary motion to said pin, whereby different wearing surfaces of said pin are successively brought into position to receive the thrust.

3. In an embossing and printing press, the combination of a reciprocable plunger, an abutment for receiving the thrust of said plunger, power devices embodying a toggle for reciprocating said plunger, a pin rotatably mounted and forming a connection for the members of said toggle, and means for automatically causing an intermittent rotary movement of said pin whereby different wearing surfaces of said pin are suc-

cessively brought into position to receive the thrust.

4. In an embossing and printing press, the combination of a reciprocable plunger, 5 an abutment for receiving the thrust of said plunger, power devices embodying a toggle for reciprocating said plunger, a pin rotatably mounted and forming a hinge connection for the members of said toggle, and 10 means operable intermittently for automatically causing a partial rotation of said pin whereby the wearing surface of said pin subjected to thrust is varied.
5. In an embossing and printing press, 15 the combination of a reciprocable plunger, an abutment for receiving the thrust of the plunger, a two part toggle power device for reciprocating said plunger having a plurality of rotatably mounted pins forming 20 thrust connections between said plunger and said toggle and between the parts of the toggle, and means for automatically causing a partial rotation of each of said pins when the toggle is broken, whereby the wearing 25 surfaces of said pins subjected to thrust are intermittently varied.

6. In an embossing and printing press, the combination of a reciprocable plunger, an abutment for receiving the thrust of the 30 plunger, power devices embodying a toggle mechanism for reciprocating said plunger, a plurality of pins each forming a hinge connection between parts of said toggle mechanism and between the toggle and the plunger, means automatically actuated for 35 intermittently causing a partial rotation of each pin whereby different wearing surfaces of said pins are successively brought into thrust positions, and means for adjusting 40 the abutment to and from the plunger.

7. In an embossing and printing press, the combination of a reciprocable plunger, an abutment for receiving the thrust of said plunger, power devices embodying a toggle 45 mechanism for reciprocating said plunger, a plurality of pins each forming a thrust connection between parts of said toggle mechanism and between it and the plunger, a bell crank movably mounted on each pin, 50 connections between said bell crank for causing substantially simultaneous actuation of said bell cranks, means automatically actuated for intermittently moving 55 said bell cranks, and means between each bell crank and the respective pins for transmitting a step-by-step movement simultaneously to each of said pins at a time when the toggle mechanism is broken.

8. In an embossing and printing press, the 60 combination of a reciprocable plunger, an adjustable abutment for receiving the thrust of said plunger, a toggle mechanism for reciprocating said plunger, a pin forming a connection between said toggle mechanism

and the plunger, a bell crank movably 65 mounted on the pin, means for causing automatic actuation of said bell crank for intermittently moving it, a ratchet wheel fixed to the pin, and a pawl carried by the bell crank whereby the oscillation of said bell 70 crank causes a step-by-step movement to be transmitted to the pin to intermittently change its surface subjected to thrust.

9. In an embossing and printing press, the combination of a reciprocable plunger, an 75 abutment for receiving the thrust of the plunger, power devices for reciprocating said plunger, a reciprocable die carriage, a guide for said carriage mounted on said plunger transversely to the direction of its 80 movement, a second guide for said carriage pivotally mounted adjacent said guides on said plunger and in alignment therewith, means to transmit movement of said plunger guides to said pivoted guides, whereby 85 both sets of said guides are always maintained in alignment, and means for reciprocating the carriage over said guides.

10. In an embossing and printing press, the combination of a reciprocable plunger, 90 an abutment for receiving the thrust of the plunger, power devices for reciprocating said plunger, a reciprocable carriage, a set of guides for said carriage carried by and movable with said plunger, a second set of 95 guides pivotally mounted adjacent to and in alignment with said first set of guides and having an interfitting connection therewith to transmit the reciprocal movement of said guides of the plunger to said pivoted 100 guides, and means to reciprocate said carriage longitudinally of both sets of guides.

11. In an embossing and printing press, the combination of a reciprocable plunger, an abutment for receiving the thrust of said 105 plunger, power devices embodying a toggle mechanism for reciprocating said plunger, pins forming hinge connections between parts of said toggle, bearing blocks having grooves in which said pins are seated on 110 opposite sides to receive the thrust, and means for automatically causing a partial rotation of said pins whereby different wearing surfaces of said pins are successively brought into position to receive the 115 thrust.

12. In an embossing and printing press, the combination of a reciprocable plunger, a reciprocable abutment for receiving the thrust of the plunger, means for imparting 120 to the plunger a relatively small movement in bringing the same into and out of printing position, means for imparting a relatively large movement to the abutment in moving it into and out of coöperation with the plunger, a reciprocable carriage carried by the plunger whereby it is moved toward and from the abutment in the printing op- 125

eration, an inking roll located in the path of movement of said carriage, a wiper for said carriage and power devices for actuating the means for moving the abutment and for moving the plunger whereby they are moved successively into printing position and in timed relation.

In testimony of which invention, I hereunto set my hand.

EDW. M. LOCKWOOD.
